UNITED STATES PATENT OFFICE.

RICHARD MARX, OF PHILADELPHIA, PENNSYLVANIA, ASSIGNOR, BY MESNE ASSIGNMENTS, TO EVANS PRODUCTS CORPORATION, OF NEW YORK, N. Y., A CORPORATION OF NEW YORK.

HECTOGRAPH.

1,210,189.

Specification of Letters Patent.

Patented Dec. 26, 1916.

Application filed May 29, 1915. Serial No. 31,253.

To all whom it may concern:

Be it known that I, RICHARD MARX, a citizen of the United States, residing in Philadelphia, Pennsylvania, have invented 5 certain Improvements in Hectographs, of which the following is a specification.

One object of my invention is to provide a duplicating or copying machine whose construction shall be relatively simple, substantial and practical and which shall have its parts so arranged as to permit of its easy 10 operation and convenient adjustment.

A further object of the invention is to provide a novel form of table structure for 15 a hectograph and particularly one in which the surface from which impressions are taken is in the form of a web extending from a roll over said table to a second roll; the invention also contemplating novel means 20 for controlling the movement of the web over the table.

Another object of the invention is to provide a hectograph of the above noted type with novel means for gaging the position of 25 the sheets of paper to be printed, as well as to improve the detail construction of the machine as a whole.

These objects and other advantageous ends I secure as hereinafter set forth, reference 30 being had to the accompanying drawings, in which,

Figures 1 and 2 are respectively a side elevation and a plan of a machine constructed according to my invention; Fig. 3 35 is a transverse vertical section of the machine shown in the other figures; and Fig. 4 is a fragmentary detached perspective view of the driving end of one of the spindles and its associated journal.

In the above drawings the frame of the machine is shown as consisting of two transversely extending end members in the form of castings 1 each including two legs 2 and rigidly connected by angles 3 which define 40 the opposite sides of said frame. On this body or frame is mounted the table top which consists of a flat plate 7 of aluminum or other suitable metal extending the full length and breadth thereof and having a

50 felt or other more or less soft fabric cover 8 whose edges extend down around and under the edges of the plate 7 where they are clamped between said plate and the adjacent surfaces of the frame. Said cover is 55 thus retained in a smooth, more or less

stretched condition over the top surface of the plate 7.

The web 10 from which impressions are to be taken consists of a paper or similar body portion provided with a suitable coating and is shown as passing from a roll 11 over a guide roller 13 at one end of the machine, thence over the flat fabric cover 8, around a second guide roller 13^a at the opposite end of the machine to a second roll 12. 60

The first roll 11 is mounted upon a spindle 14 removably supported upon a pair of journals 15 and 16 of which the first is carried by a bracket 17 depending from the frame adjacent one end of the machine. The 70 second journal is carried by a bracket 18 likewise depending from the body and preferably made of more or less resilient material permitting it to be drawn out of engagement with the end of the spindle 14. 75 The journal 15 has fixed to it a ratchet wheel 19 and a crank handle 20, while on the bracket 17 adjacent said ratchet wheel is mounted a pawl 21 so placed as to coact therewith. This pawl has a projecting arm 80 engaging a cam 22 carried on a short shaft journaled in the bracket 17 and having an operating head 23. Said cam is preferably oblong in form, being so placed that when the pawl arm is in engagement with one of 85 its long sides said pawl is in position to hold the ratchet wheel from turning while when said arm rests upon one of its short sides it is raised out of engagement with said wheel. The pawl is at all times drawn toward the ratchet wheel by a spring 5. The 90 web roll 12 is likewise carried on a second spindle 14^a carried by a pair of journals 15^a and 16^a carried on two brackets 17^a and 18^a. The journal 15^a also has fixed to it a ratchet 95 19^a and a crank handle 20^a and the former of these is acted on by a pawl 21^a, held in operative position by a spring 5^a and controlled by a cam 22^a fixed to a rotatable head 23^a and similar in form and function to the 100 cam 22. The bracket 18^a like the bracket 18 is made of resilient material and may be sprung away from the spindle 14^a to release the same.

At the ends of the machine there are provided covers 25 for the web where it leaves the table top and passes around the rolls 13 and 13^a respectively, and each of these consists of a pair of side frames 26 pivoted or hinged to lugs 27 projecting outwardly from 110

the legs 2. The two side frames 26 of each cover have their upper parts connected by a suitable body 28 of sheet metal which extends over the outer side and top of the roll 13 or 13^a as the case may be, and terminates in a flat extension 28^a immediately adjacent and substantially parallel with the table top. This extension is connected to the body by a vertically projecting portion 28^b at right angles to it, and obviously either of the covers may be swung on its pivots away from the table so as to expose the roll 13 or 13^a, with that portion of the web which passes around the same.

15 The top of the plate 28 of one of the covers 25 is provided with an elongated slot 30 for the reception of a bolt 31 whereby an adjustable abutment 32 is held adjacent the top surface of the flat extension 28^a with a flat face in a plane at right angles to the latter. Said bolt has a nut in the form of a head 33 whereby the abutment may be clamped in any adjusted position.

Under operating conditions the previously 25 coated web of paper or other material in the form of the large roll 11 is mounted upon the spindle 14 which is placed upon the two supporting journals 15 and 16, and the head 23 is so turned as to bring one of the short 30 sides of its cam 22 into engagement with the adjacent arm of the pawl 21. The opposite end of said pawl is thus raised out of engagement with the teeth of the ratchet wheel 19 and the web 10 is drawn from the roll 11 35 around the roller 13 (from which the cover 25 is thrown back,) being then led over the table top in engagement with the felt or fabric 8 thereon. The cover of the roller 13^a being also swung out of the way permits the 40 web to be passed around said roller and attached to the second spindle or roller 14^a which is supported on the journals 15^a and 16^a, after which the head 23 is turned into position to cause the cam 22 to lock the pawl 45 21 in engagement with its ratchet wheel so as to hold the roll 11 from further rotation. By means of its handle 20^a the roller 14^a is now turned slightly until the web 10 lies 50 taut over the table top, and the pawl 21^a is caused to engage the teeth of the ratchet wheel 19^a in order to retain it in this condition. The two covers 25 are then returned to the positions shown in Fig. 1, and a sheet having matter written thereon in suitable 55 ink may now be laid face down upon the coated upper face of the web 10, being positioned thereon by having its top end laid over one of the flat portions 28^a and abutted upon the adjacent part 28^b and the abutment 60 32. By any suitable means the sheet is pressed into engagement with the web 10 so that the latter is etched by the ink or other substance used in the writing, in the manner well understood in this art. After removal of the sheet and the application to

the web of suitable printing ink, blank sheets may be pressed into engagement with said web after first being brought to the proper position by having one end laid upon the flat part 28^a of one of the covers and 70 moved against the abutment 32 and the vertical part 28^b. Either cover 25 may be thus utilized to provide or support a gaging edge and whenever desired, the pawl 21 may be raised out of engagement with its ratchet 75 wheel 19 and the roller 14 turned by means of its handle 20 so as to bring new portions of the web material 10 into position upon the table top, or if desired, the pawl 21 may be left in engagement with its ratchet and 80 the pawl 21^a raised so that some portion of the web which has already been etched or impressed, may be again returned into position for re-use.

Whenever it is desired to renew the felt 85 upon the plate 7, the latter may be bodily removed from the machine by taking out the screws holding it in place. A new length of felt may then be stretched over the plate and after being carried around the ends 90 thereof, may be clamped in position by setting up the holding screws whereby the top is held to the frame.

As shown in Fig. 4, the spindles 14 and 14^a which are usually made of wood, have 95 on their ends circular metal plates 35, of which that designed for engagement with the journal 16 has a circular hole for the reception of the correspondingly formed supporting portion 36 of said journal. The 100 plate at the opposite end of each journal however, is provided with a centrally placed rectangular opening 37 designed for the reception of the wedge-shaped extremity of the journal 15 through which power is transmitted from the handle 20 or 20^a as the case may be, when the web material 10 is to be wound thereon.

I claim:—

1. The combination in a hectograph of a 11 table; spindles supported under the table; guide rollers respectively at the ends of the table; a duplicating web passing from one spindle around one of the rollers across the table, over the second roller and to the second spindle; with sheet guiding and supporting covers for each of said rollers.

2. The combination in a hectograph of a 12 table; rollers at opposite ends of said table; a duplicating web extending over the table and around said rollers; with covers for the rollers including portions serving as sheet guiding means hinged to the table structure.

3. The combination in a hectograph of a 13 table; rollers at opposite ends of said table; a duplicating web extending over the table and around said rollers; with a cover for one of said rollers having a portion placed to position upon the web the sheets to be printed.

4. The combination in a hectograph of a table; guide rollers at opposite ends of the table; a duplicating web extending over the table and around the rollers; with covers for said rollers each having a portion extending substantially parallel to the web surface adjacent the ends of the table respectively.

5. The combination in a hectograph of a table; guide rollers at opposite ends of the table; a duplicating web extending over the table and around the rollers; a transversely extending structure projecting over one of the rollers and including a portion shaped to position the end of a sheet to be printed; and an abutment on said structure for engaging one side of such sheet.

6. The combination in a hectograph of a table; guide rollers at opposite ends of the table; a duplicating web extending over the table and around the rollers; a transversely extending slotted structure extending over the rollers for positioning the end of a sheet to be printed; and an abutment adjustable longitudinally in the slot of said structure for engaging one side of such sheet.

7. The combination in a hectograph of a table; guide rollers at opposite ends of said table; a duplicating web extending over the

table and around the rollers; with covers for said rollers each having a portion extending substantially parallel to the web surface adjacent the ends of the table respectively and also including an abutment portion extending substantially at right angles to said first portion.

8. The combination in a hectograph of a frame; a table supported thereby; two pairs of brackets carried by the frame of which at least one of each pair is made to be laterally resilient; journals carried by said brackets; a handle for one journal of each pair; and spindles carried by the journals each having an opening at one end of a form other than circular designed to receive a correspondingly formed portion of that journal to which the handle is attached.

9. The combination in a hectograph of a table; pairs of brackets depending therefrom, of which one bracket of each pair is resilient; journals respectively carried by said brackets; a spindle carried by each pair of journals; and a duplicating web extending from one spindle over the table to the other spindle.
